GUN

Filed June 28, 1926

WITNESS:

Geo. W. Tippetts
INVENTOR
BY Victor J. Evans

ATTORNEY

UNITED STATES PATENT OFFICE.

GEORGE W. TIPPETTS, OF SPANISH FORK, UTAH.

GUN.

Application filed June 28, 1926. Serial No. 119,152.

My present invention has reference to a toy gun in which the impelling power for driving a stick or rod is in the nature of an elastic band, and my object is the provision of means for protecting the elastic band, for holding the same in operative position, and for accurately releasing the said band when the projectile is to be shot from the gun.

10 A further object is the provision, in a toy gun of this character, of a hammer member associated with the elastic impelling band, and a trigger member for actuating the hammer.

15 A still further object is the provision of a toy gun of this type which is characterized by simplicity in construction, cheapness in manufacture and thorough efficiency in practical use.

20 To the attainment of the foregoing, reference is to be had to the drawings which accompany and form part of this application.

In the drawings:—

25 Figure 1 is a side elevation of a toy gun in accordance with this invention.

Figure 2 is a top plan view thereof.

Figure 3 is an enlarged sectional view approximately on the line 3—3 of Figure 2.

30 Figure 4 is a sectional view on the line 4—4 of Figure 1.

Figure 5 is a fragmentary elevation to illustrate another manner in which the elastic band may be secured to the gun.

35 The gun proper is constructed of wood to include a barrel 1 and a stock 2. The barrel 1 has its outer edge grooved longitudinally, as at 3, throughout the length thereof, and the said barrel terminates in a slightly 40 rearwardly inclined shoulder 4. The groove 3 extends centrally through the shoulder 4 and the inner wall provided by this portion of the groove is deepened and is preferably rounded, as at 5. The under face of the barrel, adjacent the outer end thereof, has secured thereon a staple 6, and received through this staple there is an endless elastic element 7. It may, however, be found preferable to secure the ends of the elastic or like 45 rubber band 7 to the sides of the barrel by clips 6' as illustrated in Figure 5 of the drawings. The inner loop of the elastic impelling element 7 has arranged there-

around a non-elastic band 9, whose outer end is fixedly secured to a button 10. The button is designed to rest against the shoulder 4 when the band 7 is stretched, and the outer end or loop of the band 7 is designed to be received in a depression 11 in a cross sectional rounded stick 12 that provides the projectile. It is to be noted that the non-elastic band 9 receives the round portion of the elastic element 7 therethrough and consequently the non-elastic member will be received in the depression 11 of the stick 12, thus affording a protection to the elastic band to prevent the same wearing and becoming easily broken by direct contact with the stick. It will be also noted that this portion of the non-elastic band 9 not only 60 serves as a protector but also as a cushioning element for the elastic band 7.

Passing through an opening 13 in the gun, at the juncture of the stock and barrel, there is a wooden or like pin 14. The pin 75 passes through the deepened inner portion of the longitudinally extending groove 3 and is received between the walls thereof so that the axial center of the said stick is arranged approximately in a line with the shoulder 4. This arrangement is believed clearly illustrated by Figures 3 and 4 of the drawings. The pin is disposed directly below and is normally in contact with the button providing the hammer 10. The 80 lower end of the trigger 14 is preferably secured to a flexible guard 15 and the ends of this guard are tacked or otherwise secured to the under face of the gun. A pressure 85 on the guard will raise the hammer 10 from the shoulder 4 and permit the contraction of the band 7, which, of course, impels the projectile 12 through the groove 13 of the barrel.

The simplicity of the construction will, 95 it is thought, be apparent.

Having described the invention, I claim:—

A toy gun comprising a barrel and a stock, and said barrel having its upper edge grooved throughout the length thereof, and merging, at its inner end into a slightly inclined shoulder, and the groove for a short distance from said shoulder being beaded, an elastic element having its ends fixed on the sides of the barrel and carrying a button 100 to be received on the shoulder, said gun, in 105

a line with the shoulder having a round opening therethrough and the shoulder having a central notch extending therethrough in a line with the outer wall provided by the opening, and a cross sectionally rounded pin designed to be received through the opening and the notch to contact with the

button when the latter rests on the shoulder and an arched flexible guard having its ends secured to the gun and to which the pin is centrally connected.

In testimony whereof I affix my signature.

GEORGE W. TIPPETTS.
